FILTER

John W. Fitz Gerald, Milwaukee, Wis., assignor to
 Briggs & Stratton Corporation, Milwaukee,
 Wis., a corporation of Delaware

Application August 9, 1935, Serial No. 35,502

2 Claims. (Cl. 210—131)

This invention relates to improvements in filters and has as an object to provide an improved oil filter for internal combustion engines.

Another object of this invention is to simplify the construction and reduce the cost of oil filters for use with pressure lubricating systems of internal combustion engines.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates two complete examples of the physical embodiment of the invention constructed according to the best modes so far devised for the practical application of the principles thereof, and in which:

Figure 1 is a longitudinal section view through a filter unit embodying this invention;

Figure 2 is a greatly magnified cross section view through a portion of the filter unit per se; and

Figure 3 illustrates a portion of a filter unit of slightly modified construction.

Referring now more particularly to the accompanying drawing, the numeral 5 designates the casing of the filter unit, which, as is customary, is provided with inlet and outlet nipples 6 and 7, respectively. The inlet and outlet nipples are connectible with the pressure lubricating system of an internal combustion engine in the conventional manner so as to conduct lubricant under pressure into the interior of the casing and to return filtered lubricant back into the system.

Attached to the outlet nipple 7 and extending down into the interior of the casing 5 is a hollow perforated core 8. Surrounding this core and tied thereto as at 9 is a bag 10. The bag 10 is of a size to fill the major portion of the interior of the casing 5 and may be composed of ordinary cloth, or as shown in Figure 3, may have its wall composed of outer and inner cloth layers 11 and 12, respectively, with a layer of filter paper 13 disposed therebetween.

The bag is loosely filled with a suitable loose finely divided material 14 which has a degree of natural resiliency and an ability to filter lubricant passed therethrough. Ordinary sawdust has been found to be very well suited to the

purpose of this invention although other materials such as loosely carded animal wool, cotton waste, ground cork, and similar materials, may be employed with good results.

To prevent the passage of the bag contents 5 through the perforations 15 in the hollow core, a screen 16 surrounds the core.

As stated, the bag is but loosely filled and its contents have a degree of natural resilience so that fluid pressure within the casing 5, more or less collapses and deforms the bag from its normal shape depicted in dotted lines in Figure 1, to a compressed state shown in full lines. Upon reduction in the fluid pressure within the casing 5, the expansion of the bag contents because of 10 its natural resilience causes internal motion of the bag contents and continuously rearranges the particles thereof and presents an ever changing relationship between the wall of the bag and its contents so that the filter unit by its own 15 inherent action is kept from clogging.

Tests have shown that the performance of the filter of this invention equals and exceeds that of filters heretofore in use regardless of their cost. No irrefutable or conclusive explanation of 20 how the construction here presented gains its advantage over past filters has been established, but it is believed that the success of the unit is due primarily to the fact that under compression the inner surface of the bag wall is forced into 25 close juxtaposition with the bag contents so that through the coaction of the wall of the bag and the outer layer of its contents, filtering interstices are provided which otherwise would not be 30 present.

The performance of the unit is improved through the use of a multiple layer wall for the bag such as illustrated in Figure 3, but the advantages of this multiple layer construction over the single layer are not so pronounced as to indicate that the primary filtering action is obtained 35 by the wall of the bag per se; and tests with different materials in the bag indicate that the effectiveness of the unit is not dependent upon the nature of the bag contents.

But tests with constructions using only the loose material, even though it is held about a perforated core by means of an open mesh screen or the like, show a marked reduction in effectiveness.

From these tests, the theory suggested hereinbefore has been deduced, namely, that a novel coaction exists between the bag wall and its contents upon compression of the unit to provide fil-

tering interstices which otherwise are not present; and that the constant internal motion resulting from variations in the fluid pressure on the bag keeps rearranging the particles of the bag contents and prevents clogging.

From the foregoing description taken in connection with the accompanying drawing, it will be readily apparent to those skilled in the art to which this invention appertains, that this invention provides a filter unit of exceptionally simple and inexpensive construction.

What I claim as my invention is:

1. A filter device connectible with a pressure lubricating system of an internal combustion engine and comprising a casing having an inlet connectible with the lubricating system to receive lubricant under pressure and an outlet for filtered lubricant, a hollow perforated core connected with the outlet and disposed wholly within the casing, and a cloth bag enclosing the perforated portion of the core and containing a quantity of sawdust, said sawdust being loosely packed in the bag so that the bag is readily deformed and its sawdust contents placed in compression by fluid pressure within the casing to expand upon a reduction in the fluid pressure within the casing and thereby produce internal motion within

the contents of the bag upon each variation of fluid pressure.

2. A filter device connectible with a pressure lubricating system of an internal combustion engine and comprising a casing having an inlet connectible with the lubricating system to receive lubricant under pressure and an outlet for filtered lubricant, a hollow perforated core connected with the outlet and disposed wholly within the casing, a fabric bag disposed within the casing with the perforated portion of the core inside the bag, and loose material filling the bag around the perforated core, said material being capable of a filtering action and being inherently resilient and loosely packed in the bag so that the bag is readily deformed and its contents placed in compression by lubricant introduced into the casing under pressure and passing through the bag contents to the perforated core, and whereby fluctuations in fluid pressure within the casing results in expansion and contraction of the bag contents due to its inherent resiliency to cause internal motion of the bag contents so that different portions of the bag contents are constantly presented to the inside surface of the bag.

JOHN W. FITZ GERALD.
